UNITED STATES PATENT OFFICE.

CHARLES P. BECKWITH, OF DETROIT, MICHIGAN, ASSIGNOR TO PARKE, DAVIS & COMPANY, OF DETROIT, MICHIGAN, A CORPORATION OF MICHIGAN.

APPARATUS FOR DISCHARGING LIQUIDS IN MEASURED QUANTITIES.

1,030,378.

Specification of Letters Patent.

Patented June 25, 1912.

Application filed July 23, 1908. Serial No. 444,982.

To all whom it may concern:

Be it known that I, CHARLES P. BECKWITH, a citizen of the United States of America, residing at Detroit, in the county 5 of Wayne and State of Michigan, have invented certain new and useful Improvements in Apparatus for Discharging Liquids in Measured Quantities, of which the following is a specification, reference being had 10 to therein to the accompanying drawings.

It is the object of the invention to obtain means for automatically measuring and discharging predetermined volumes of liquid, being more particularly designed for use in 15 filling bottles, and other liquid containers.

To this end the invention consists in the construction of a measuring device which is filled by a constant supply connection and is periodically discharged by siphonic action.

20 The invention further consists in the means employed for varying the volume of the liquid measured, and, further, in the peculiar arrangement and combination of parts as hereinafter set forth.

25 In the drawings—Figure 1 is a vertical section through the apparatus; Fig. 2 is a perspective view of a modified construction.

My improved apparatus comprises essentially a modified construction of intermittent siphon. This device which has been variously used in the arts for discharging liquids from a receptacle consists of an inverted U-shaped tube having one leg longer than the other, the short leg being in communication with the vessel from which the liquid is to be discharged. Thus if the level of the liquid in this receptacle is caused to rise above the bend in the tube, the siphon will be started and will continue in action 30 until the level falls below the lower end of the short leg, whereupon air is admitted to break the siphon. With the construction forming the subject matter of the present invention accurately measured volumes of 35 liquid are periodically discharged by an adaptation of an intermittent siphon, and the arrangement is such that the volume discharged may be varied.

As illustrated, A is a supply connection 50 for the liquid to be measured in which a constant rate of flow is maintained preferably by connecting the conduit to a supply tank B having a float valve C or other equivalent means for maintaining a constant 55 level of the liquid therein. The supply pipe

A is connected with a measuring device D and this in turn is connected with the siphon E by which the liquid is periodically discharged. In the specific form illustrated, the measuring receptacle D is formed by a 60 U-shaped tube, one leg *a* of which also constitutes the short leg of the siphon. The long leg *b* of the siphon is formed by a tube of lesser diameter than the measuring receptacle and extends downward below the 65 bend *c* in the U-shaped tube a sufficient distance to produce the desired siphonic action. The other leg *d* of the U-shaped tube extends above the bend *e* connecting the short and long legs of the siphon and thus 70 the liquid admitted to the supply connection A is free to rise in the tube *d* above the level of the bend *e*.

With the construction as thus far described, a constant flow of the liquid is 75 maintained in the tube A which entering the measuring receptacle D will rise therein until the level of the bend *e* is attained. This will permit the liquid to pass over into the long leg of the siphon, which is immediately started into action, and as this siphon is proportioned to have a higher rate of discharge than the inflow from the tube A the level liquid in the measuring receptacle will fall. As soon as this reaches 80 the lower bend *c* of the U-shaped tube, air will be admitted into the tube *a*, which rising through the liquid will break the siphon and prevent further discharge. The liquid remaining in the tube *a* will then fall backward 85 equalizing the level in both legs of the U. During the operation just described, the inflow of the liquid from the tube A will continue and therefore the volume of liquid discharged is in excess of the volume in the 90 tube *d* at the time the siphon is started. However, as the rate of inflow is constant the volume discharged may be readily predetermined. I preferably also provide means for varying the volume discharged, 95 and this may be accomplished in different ways. Thus by means of a valve F in the supply conduit A the rate of inflow may be varied, or again the rate of outflow could be altered by changing the length of the 100 long leg *b* of the siphon. Any variation in these factors will of course alter the volume of liquid discharged. A further means of variation is an alteration in the capacity of the measuring receptacle D and, as shown, 105 110

such a variation is produced by the adjustment of a small tube G within the tube d. The tube G passes through an aperture in the stopper H for the tube d, and may be 5 raised or lowered, as desired. The lowering of the tube will decrease the capacity of the measuring receptacle, for the reason that as soon as the lower end of the tube G is sealed by the rising liquid the air contained 10 in the tube d above the level will be trapped and further rising of the liquid in said tube is prevented, but it continues to rise in the small tube G until the siphon is started. Thus the capacity of the measuring 15 receptacle is altered by any adjustment of the tube G.

The tube G, in addition to forming a means for altering the capacity of the measuring receptacle, performs the further function of regulating the discharge. This is due 20 to the restriction imposed upon the incoming air which displaces the liquid in the measuring receptacle after the starting of the siphon. As a consequence, the rate of discharge in successive operations is more uniform than would be the case if the full area 25 of the tube d were in communication with the external atmosphere.

In the use of the apparatus above described for placing measured quantities of liquid in containers, it is only necessary for the operator to successively place the empty container in registration with the discharge tube b, the transfer occurring during the interval 30 in which the siphon is broken and the liquid is accumulating in the measured receptacle. It is obvious that the transfer may be performed by automatic means if desired, but such means forms no part of 35 the present invention.

The modified construction illustrated in Fig. 2 is a multiple machine comprising a series of adjacent devices, each being substantially the same construction as illustrated 45 in Fig. 1. With such a construction a large number of containers may be simultaneously filled with the measured quantity of liquid. It is, however, necessary to provide means for causing the individual members of the 50 series to operate synchronously, as otherwise the transfer of the containers could not be conveniently performed. This synchronous action may be accomplished by cross-connecting all of the supply conduits A for the 55 several measuring receptacles by an equalizing tube I, which will cause the liquid in all of the various measuring receptacles to stand at the same level. Thus, all of the receptacles will be simultaneously discharged, and 60 the removal of the filled containers and the positioning of the empty containers may be accomplished during the interval in which the measuring receptacles are being filled.

What I claim as my invention is:

65 1. A device for successively filling recep-

tacles with a predetermined volume of liquid comprising a siphon having a discharge leg registerable with the receptacle to be filled, a measuring receptacle communicating with said siphon, of predetermined capacity between the levels for starting and breaking the flow, and an inlet for said measuring receptacle having a lesser rate of flow than the discharge from the siphon. 70

2. A device for successively filling receptacles with a predetermined volume of liquid comprising a siphon having a discharge leg registerable with the receptacle to be filled, a measuring receptacle communicating with said siphon and of predetermined capacity 75 between the levels for starting and breaking the flow, an inlet for said measuring receptacle having a lesser rate of flow than the discharge from the siphon, and means for varying the quantity of liquid discharged. 80

20 3. A device for successively filling receptacles with a predetermined volume of liquid comprising a siphon having a discharge leg registerable with the receptacle to be filled, a measuring receptacle communicating with said siphon of predetermined capacity 85 between the level for starting and breaking the flow, an inlet for said receptacle, having a lesser rate of flow than the discharge of the siphon, and means by which the relation between the inlet, discharge and the capacity of the measuring receptacle may be varied to alter the measurement of the quantity discharged. 90

25 4. The combination of a series of measuring receptacles, means for continuously supplying liquid thereto and for equalizing the levels in the several receptacles, and siphonic discharge connections for said receptacles automatically and synchronously operating 100 between predetermined levels of the liquid 105 therein.

30 5. A measuring device comprising a siphon having its short leg terminating in a rebent portion of greater length than said leg, a supply connection communicating with said rebent portion, and means for continuously supplying liquid to said connection. 110

35 6. A measuring device comprising a siphon having its short leg terminating in a rebent portion of greater length than said leg, a supply connection communicating with said rebent portion, means for continuously supplying liquid to said connection, and means for varying the effective capacity 115 of said re-bent portion. 120

40 7. A measuring device comprising a siphon having its short leg terminating in a rebent portion of greater length than said leg and having its long leg of smaller cross-section than said short leg, a supply connection communicating with said rebent portion, and means for continuously supplying liquid to said connection. 125

45 8. A measuring device comprising a si- 130

phon having its short leg terminating in a
rebent portion of greater length than said
leg and having its long leg of smaller cross-
section than said short leg, a supply con-
nection communicating with said rebent
portion, means for continuously supplying
liquid to said connection, and an open-ended
tube within said rebent portion adjustable in

relation thereto for varying the effective ca-
pacity of said re-bent portion.
